UNITED STATES PATENT OFFICE.

KARL ENGEL, OF ARLINGTON, MASSACHUSETTS, ASSIGNOR TO UNITED SHOE MACHINERY COMPANY, OF PATERSON, NEW JERSEY, A CORPORATION OF NEW JERSEY.

FASTENER FOR SHOE-UPPERS.

1,150,854.

Specification of Letters Patent. Patented Aug. 24, 1915.

Application filed October 8, 1912. Serial No. 724,571.

To all whom it may concern:

Be it known that I, KARL ENGEL, a citizen of the United States, residing at Arlington, in the county of Middlesex and 5 State of Massachusetts, have invented certain Improvements in Fasteners for Shoe-Uppers, of which the following description, in connection with the accompanying drawings, is a specification, like reference characters on the drawings indicating like parts in the several figures.

This invention relates to shoe fastening devices for securing together the eyeleted edges of shoe uppers. 15 In the manufacture of boots and shoes, it is frequently desirable or necessary to secure the eyeleted edges of an upper together temporarily in order to hold the said edges from being unduly spread apart when 20 the upper is under tension, for example, during lasting or relasting operations.

An object of the invention is to provide an improved shoe fastening device so constructed and arranged that, whenever during 25 the bottoming of a shoe the upper is thus put under tension, not only will the eyeleted edges of the upper always be held against excessive spreading but also danger of injuriously straining or tearing the upper 30 will be obviated.

To this end, the invention, as preferably embodied, comprises means for engaging and retaining opposite eyelets of an upper and a spring connection between these means 35 so constructed and arranged that when the tension incident, for example, to the lasting operation is put upon the upper, the eyelet engaging and retaining means will be caused to put a sufficient opposing tension 40 on the eyeleted edges of the upper in directions tending to draw the said edges together to maintain them properly spaced during the lasting or other operation. At the same time, this yielding connection between 45 the eyelet engaging and retaining means permits the said means to separate sufficiently under excessive and abnormal strains to insure that the upper will not be damaged as by injuriously straining or 50 tearing the vamp. Furthermore, the illustrated construction and arrangement are such that the opposing tension put on the eyeleted edges of the upper by the fastening device is so applied as to cause the said

edges and adjacent portions of the upper to 55 conform closely to the last whatever its contour and whatever the style of the shoe.

Another object of the invention is to provide a fastening device for shoe uppers adapted for use also as a shoe upper carrier 60 and hanger. To this end, in fasteners embodying the present invention, the spring connection between the eyelet engaging and retaining means preferably comprises a spring loop constituting a carrier and 65 hanger arranged to be used either for carrying unlasted uppers or lasted shoes from one place to another or, where shoe racks comprising series of spindles or rods are employed, to be used for stacking unlasted 70 uppers upon the spindles or rods of such racks.

These and other features and advantages of the present invention, including certain details of construction and combinations of 75 parts, will appear from the following detailed description read in connection with the accompanying drawings.

Referring to the drawings: Figure 1 is a view of a shoe, partly in section, looking 80 at the shoe from in front and slightly above the shoe, and showing one embodiment of the present invention applied thereto; Fig. 2 is a side elevation of a modification of the form of fastener shown in Fig. 1. Fig. 3 85 is an angular perspective of another modification applied to a rod of a rod shoe rack; Fig. 4 is an angular perspective of a plurality of fasteners embodying the present invention shown in connection with a rod 90 of a rod shoe rack.

The illustrated fastening device comprises a single piece of spring metal, preferably of rather stiff tempered steel wire, bent back upon itself near its center to form 95 a loop or ring 2 terminating in crossed oppositely extending legs 4 in sliding engagement near their point of intersection 6 and carrying open eyelet engaging and retaining hooks 8 adapted to enter opposed eyelets 10 of a shoe upper top A, the upper top A illustrated being of the co-called Blucher type. Preferably, as shown, the eyelet engaging and retaining hooks 8 are in the plane of the legs 4 and the free end 100 of each hook 8 extends parallel to the adjacent leg 4.

The eyelet engaging and retaining hooks

S are, in the form illustrated in Fig. 1, in-turned so as to have their free ends located on the inner side of the upper when the fastening device is in use, this construction being especially designed to prevent the ends of the hooks 8 from marring or defacing the vamps of adjacent uppers of a pile of uppers stacked together. In the modified forms shown in Figs. 2 and 3, however, the hooks 8 are oppositely directed so that, when in use, the ends of the said hooks will be located on the outer side of the upper top A, the outturned hooks possessing the advantage of obviating any danger of marring the vamp, indicated generally at B, of which there is sometimes liability in the use of the device in connection with shoes having very high insteps.

The above described construction and arrangement are such that the loop or ring portion 2 of the fastening device constitutes a spring connection between the eyelet engaging and retaining hooks 8 which connection causes the said hooks 8 to tension the eyeleted edges of an upper sufficiently in directions tending to draw the said edges together to prevent excessive separation of the eyeleted edges of the upper at any time during the lasting operation. At the same time, the spring connection between the hooks 8 permits them to yield sufficiently under abnormal and excessive lasting strains to prevent unduly straining the vamp B and thus weakening or breaking it, particularly in the regions indicated at 12 where the lasting strain is great and the vamp relatively weak. Furthermore, as will be clearly apparent from Fig. 1, the noses, indicated at 14, of the Blucher top A are held down flat on the vamp B.

It will be understood that, by reason of the yielding character of the above described connection between the eyelet engaging and retaining hooks 8, the eyeleted edges of an upper are not kept at a mathematically unvarying distance apart at all times when under tension due to the lasting or other bottoming operations. The construction is such, however, as to prevent objectionable variations in the distance of the said edges apart at any time. Moreover, from an assortment of fastening devices differing somewhat in the normal distance apart of the terminal portions of the hooks 8, a selection can be made appropriate to the particular pattern of a given upper in connection with which the fastener is to be employed so as to insure proper results in the use of the fastening device even in connection with uppers of widely different patterns.

Another advantage of the above described yielding connection between the eyelet engaging and retaining hooks 8 consists in the fact that this yielding connection facilitates inserting the hooks 8 in or removing

them from the eyelets 10 of an upper while a last is in the shoe and the upper is under tension.

The illustrated fastening device, as above suggested, is designed for use also as an upper carrier and hanger, the loop or ring portion 2 of the fastening device constituting a bail hanger by which the fastener and upper or lasted shoe carried thereby may be taken from place to place or by means of which, as illustrated in Figs. 3 and 4, uppers may be stacked on rods 16. In the modified form shown in Fig. 3, the crossed legs 4 of the fastening device are bent near their point of intersection 6 to cause the ring or loop portion 2 to lie in a plane angularly disposed to the plane of the legs 4 with a view to better adapting the device for use in stacking uppers upon vertical rods as illustrated in Fig. 2, and for the purpose of further providing against marring of the vamp B.

Having fully explained my invention and described the manner in which the same may be embodied, what I claim as new and desire to secure by Letters Patent of the United States is:—

1. A shoe fastening device for securing together the eyeleted edges of a shoe upper comprising open hooks shaped to enter and retain opposed eyelets and a spring loop constructed and arranged to draw said hooks toward each other with sufficient force to maintain said eyeleted edges properly spaced when the upper is under tension during lasting and other operations while permitting said hooks to yield under excessive or abnormal strains to prevent damaging the upper, said spring loop being constructed and arranged to serve as a carrier and hanger for the upper.

2. A shoe fastening device for securing together the eyeleted edges of a shoe upper comprising a spring loop terminating in crossed legs carrying open hooks in the plane of said legs and shaped to enter and retain opposed eyelets, said spring loop resiliently drawing said hooks toward each other so as to maintain said eyeleted edges properly spaced when the upper is under tension during lasting and other operations.

3. A shoe fastening device for securing together the eyeleted edges of a shoe upper comprising a spring wire bent to form a spring loop terminating in oppositely extending legs carrying open hooks for engaging and retaining opposed eyelets, each of said hooks terminating in a free end substantially parallel to the adjacent leg and said spring loop resiliently drawing said hooks toward each other so as to prevent improper separation of said eyeleted edges when the upper is under tension.

4. A fastening device for shoe uppers comprising a piece of spring wire bent back

upon itself to form a loop and having its legs extended beyond their point of intersection to form eyelet engaging and retaining members, said wire being further bent 5 at or near the intersection of its legs to cause the loop portion of the fastener to lie in a plane angularly disposed to the plane of the legs.

Copies of this patent may be obtained for five cents each, by addressing the "Commissioner of Patents, Washington, D. C."

In testimony whereof I have signed my name to this specification in the presence of 10 two subscribing witnesses.

KARL ENGEL.
